UNITED STATES PATENT OFFICE.

WILLIAM J. NOON, OF LYNN, MASSACHUSETTS, ASSIGNOR OF ONE-HALF TO SIMEON J. ROUSSEAU, OF LYNN, MASSACHUSETTS.

COUNTER-GUARD.

1,000,111.

Specification of Letters Patent. Patented Aug. 8, 1911.

Application filed May 27, 1908. Serial No. 435,295.

To all whom it may concern:

Be it known that I, WILLIAM J. NOON, of Lynn, in the county of Essex and State of Massachusetts, have invented certain new 5 and useful Improvements in Counter-Guards, of which the following is a specification.

This invention relates to guards used in connection with heel-trimming machines, to 10 protect the upper at the counter of the shoe from being scratched or otherwise injured by the cutter.

The invention particularly relates to a manner and means of mounting the guard 15 so that it may move away from the cutter when the higher or thicker part of the heel is turned toward the same, and will be guided in so moving in a path which conforms to the final curvature of the heel edge, which 20 is the same as the curvature of the cutting edges of the cutter blades.

It is accordingly the object of my invention to enable a shield for guarding the counter of a shoe to be mounted in such a 25 way that it may move outward longitudinally toward and beyond the end of the cutter from its innermost position, wherein it somewhat overlaps the cutter, and in so moving, will be guided in the desired path.

Another object is to enable the path in 30 which the shield moves to be varied correspondingly to different styles of heels, so that the same device, except for a change in the guiding member, may be used in the 35 trimming of shoe heels of a variety of styles.

In carrying out my invention so as to attain the objects stated, I have devised an attachment for heel-trimming machines, carrying a holder to which is secured a shield, 40 with supporting devices for the holder permitting it to move both longitudinally and transversely of the axis of the cutter, and with a guide against which the shield holder is caused to bear, and by which the path 45 wherein it moves is determined.

The preferred embodiment of the invention is illustrated in the accompanying drawing drawings, in which,—

Figure 1 represents a plan view of the device in the relation which it occupies to the cutter of a heel-trimming machine, Fig. 2

represents an elevation of a part of the device, as seen from the right of Fig. 1.

The same reference characters indicate the same parts in both figures.

Referring to the drawings, 1 represents the rotary cutter of a heel-trimming machine, and 2 the bearing in which its shaft rotates. This may be the cutter of any of the types of heel-trimming machine which 60 are well known and now in use, and the attachment forming the subject of this invention is adapted to be mounted upon any one of such machines. The attachment consists of a bracket 3 which is detachably securable 65 to a trimming machine in such a position that the guard or shield to be presently described, will be located in its proper relation to the cutter. This bracket contains a guide-way in which is mounted a slide 4 carrying 70 the members which support the counter-guard. This slide is adjustable in the guide-way and is held between two undercut gibs, one of which is adjustable so as to clamp the slide in any position, the adjusting means 75 consisting of a bolt 7 passing through ears on the gibs and a clamp 8 screwed on the end of the bolt, which may be turned so as to bear against the adjacent gib and draw the head of the bolt against the other gib. 80 An adjustable screw 9 in a rib 10 of the bracket 3 limits the motion of the slide inward.

On an arm or plate 11 forming a part of the slide 4 are pivoted two swivels or lugs 12 85 13, one being on each side of the plate and mounted on the same pivot-pin 14. These swivels are provided with lugs or sleeves 15 through which pass rods or arms 16, there being one carried by each of the swivels. 90 These rods are capable of moving longitudinally in the lugs and together with the swivels, form pivotally-mounted arms to the outer ends of which is connected by means of pivot screws 17, the guard-holder 18 95 which carries the counter-guard shield 19. This shield is a curved plate which is adapted to lie near the periphery of the trimming cutter and partly embrace the same, its outer edge being flared outwardly and adapted to 100 enter the groove between the counter and sole of a shoe at the heel seat.

The holder 18 is formed with integral extensions 20 at the opposite sides, which extensions merge into one another and are provided with lugs 21 between which is pivoted the end of a link 22. The other end of this link is pivoted to a stud 23 which is contained and guided in a plate 24 in the bracket plate 11. An adjusting screw 25 provided with a wing-nut 26 is passed 10 through the plate 11 longitudinally of the slot, and prevented from moving longitudinally by the wing-nut 26 and a nut 27 threaded on its opposite end. This screw is threaded through the stud 23 and when 15 rotated, serves to move the stud in the slot, and thereby projecting the link 22 and extension 20 more or less from the edge of the plate 11. The other end of the holder 18 carries a roll 28 which is adapted to bear 20 against the outer surface of a block or plate 29 which I call for convenience a templet, that serves as a guide for determining the path in which the counter-shield 19 shall move. The roll 28 is held against the tem- 25 plet by the action of springs 30 surrounding the rod 16 and pressing between one of the sleeves 15 and an adjustable abutment 31. The roll 28 is adjustable with reference to the holder 18, being mounted in a head 32 30 having a threaded stem 33 which passes through the side of the holder and through a strap 34 secured thereto. Between the body of the holder and the strap is an adjusting nut 35 threaded upon the stem 33. 35 The latter has a longitudinal groove (not shown) into which a projection of the holder extends, so that the stem cannot turn. Thereby rotation of the stem 33 serves to move the roll 28 nearer to or farther from 40 the holder. It is secured in any position by a lock-nut 36 threaded upon the stem, which is clamped against the outer side of strap 34. By adjusting the position of the roll 28, and of the pivot stud 23, the holder 18 45 may be located at different distances from the body of the slide by which it is carried, and thereby the shield 19 may be adjusted to lie at any desired distance from the cutting edges of cutters of various sizes and 50 shapes.

The shield is adapted to move longitudinally of the cutter by reason of the pivotal connection of the shield holder 18 to the arms 16 and 22. It is held in the position 55 shown in Fig. 1, by springs 37 of which one is attached to each of the rods 16 and adjustably connected with the supporting plate 11 by an eye-bolt 38 passing through a stud 39 on the plate 11, and carrying an 60 adjustable nut 40 on the opposite side of the nut from the spring. The tension of this spring tends to swing the pivoted arms 16 to the right, and to carry and hold the link 22 against a stop 41 which is adjustable, and

consists of a set-screw threaded through a 65 lug 411 on the plate 11. Another means for thus moving and retaining the holder 18 and shield 19 is found in the springs 42 coiled around the hubs of the swivel yokes 12 13, there being one spring for each yoke, 70 one end of the spring being fastened to the yoke and the other to a stud 44 mounted upon the plate 11. The springs 37 and 42 perform the same function and may be used together, or either may be used alone, the 75 other being eliminated.

Up-and-down movement of the holder is prevented both by the rods 16 and stationary supports or rests 45 46 which extend outward from posts 47 48 and embrace between them the extensions 20 of the holder. The outer ends of these rests 45 are provided with tubular rollers 49 which diminish the friction between the extensions and 80 rests. 85

The shield is used in the usual manner in the operation of trimming a shoe heel. The shoe is placed with its tread against the flange of the cutter and the edge of the shield 19 is inserted in the heel-seat groove. 90 As the shoe is turned during the operation of trimming the heel and the rear or thicker part of the heel comes adjacent the shield, the latter is moved away from the cutter in a longitudinal direction, and is constrained 95 by the tension of the springs 30 and the reaction of the templet 29 to travel in the path determined by the surface of the templet on which the roll 28 bears. This path is made to correspond with the edge outline 100 of the cutter blades, and is consequently that of the heel when finished.

Movement of the shield in a path suitable for heels of other shapes is provided for by making the templet removable. To this end 105 the templet is formed as a block having a stem 50 which is set into a hole 51 in the edge of the plate 11, and is secured by a thumb-screw 52. The templet may be withdrawn and replaced by another having a 110 different outline on its bearing face.

I claim:—

1. The combination with a rotary heel-trimming cutter of a counter guard partially surrounding said cutter, a swivel 115 mounted to oscillate about an axis transverse to the axis of the cutter and at one side thereof, an arm connected pivotally to the guard and held in said swivel perpendicularly to the axis thereof, being movable 120 longitudinally in the swivel, a guide beside the guard, and a spring acting on said arm in a direction such as to press the guard toward said guide.

2. The combination with a rotary heel-trimming cutter of a counter guard partially surrounding said cutter, a swivel 125 mounted to oscillate about an axis transverse

to the axis of the cutter and at one side thereof, an arm connected pivotally to the guard and held in said swivel perpendicularly to the axis thereof, being movable longitudinally in the swivel, a guide beside the guard, a spring acting on said arm in a direction such as to press the guard toward said guide, and a spring arranged to turn the swivel in a direction such as to move the 10 guard axially of the cutter in a direction from the outer toward the inner end thereof.

3. The combination with a rotary heel-trimming cutter of a counter guard partially surrounding said cutter, an arm supporting said guard and pivotally mounted on an axis transverse to and at one side of the axis of the cutter, the arm being also movable radially, a guide for the guard, and a spring acting on said arm to move the 15 same and the guard into guiding relation with the guide.

4. A counter-guard for heel-trimming machines, comprising, in combination with a trimming cutter, a shield adapted to enter 20 the heel-seat groove of a shoe, a holder for said guard, pivoted arms by which said holder is carried, springs acting on said arms to hold the guard yieldingly close to the cutter, a guide plate, and springs causing 25 the holder to bear yieldingly against said guide plate.

5. A counter guard for heel-trimming machines, comprising, in combination with a trimming cutter, a shield adapted to enter 30 the heel-seat groove of a shoe, a holder for said guard, pivotally mounted arms by which said holder is carried, said arms being longitudinally movable in the pivots thereof, springs acting on said arms to hold 35 the guard yieldingly with its edge close to the periphery of the cutter, and a guide member against which the holder is yieldingly held, said guide member having an outline similar to the line from the tread to 40 the seat of the heel to be trimmed.

6. A counter-guard for heel-trimming machines, consisting of a shield, a templet, and springs acting on said shield to press it 45 respectively parallel with and against said templet normally near one end thereof, the templet having a single guiding surface whereby the shield may be moved freely away therefrom.

7. A counter-guard for heel-trimming machines, consisting of a shield having an edge adapted to enter the heel-seat groove of a shoe, movable holding means for said shield including separated, independently pivoted arms or links, means for adjusting 50 the pivot of one of said arms or links, and guiding means with which a portion of said holding means is retained in contact and having an outline corresponding with the 55 outline from top to bottom of a heel to be

trimmed, whereby the shield in being moved 65 is guided in a path conforming to the outline of the heel.

8. A counter-guard for heel-trimming machines, consisting of a shield, a holder therefor, an arm connected to said holder, 70 a pivoted bracket in which said arm is held and is longitudinally movable, a guide plate, a spring acting on said arm to draw the holder against said guide plate, and a spring tending to move the holder toward 75 one end of the guide plate.

9. A counter-guard for heel-trimming machines, consisting of a shield, a holder to which said shield is attached, having an extension, a pivotally mounted supporting 80 arm pivoted to said holder, a guiding link pivoted to said extension, means for shifting the pivot of said link, a guide plate, and means causing said holder to bear against 85 said guide plate.

10. A counter-guard for heel-trimming machines, consisting of a shield, a holder to which said shield is attached, having an extension, a pivotally-mounted supporting 90 arm pivoted to said holder, a pivotally-mounted guiding link pivoted to said extension, a guide plate, and an anti-friction roll carried by said holder and adapted to bear and hold yieldingly against said guide plate to cause the holder and shield to move in a 95 path determined by the shape of the plate.

11. A counter-guard for heel-trimming machines, consisting of a shield, a holder to which said shield is attached, having an extension, a pivotally-mounted supporting 100 arm pivoted to said holder, a pivotally-mounted guiding link pivoted to said extension, a guide plate, and an anti-friction roll carried by said holder and adapted to bear against said guide plate to cause the holder 105 and shield to move in a path determined by the shape of the plate, said roll and the pivot of said link being adjustable to shift the path in which the shield moves.

12. A counter-guard for heel-trimming 110 machines, consisting of a shield, a holder to which said shield is attached, having an extension, a pivotally-mounted supporting arm pivoted to said holder, a guiding link pivoted to said extension, a guide plate, 115 means causing said holder to bear against said guide plate, and a fixed rest against which said holder extension rests and by which it is supported.

13. A counter-guard for heel-trimming 120 machines, consisting of a bracket adapted to be secured to the machine bed, a swivel mounted on said bracket, an arm carried by and longitudinally movable in said swivel, a stud adjustably mounted in said bracket, 125 means for adjusting said stud, a link pivoted to said stud, a shield-holder pivoted to said arm and link at separated points, a

counter shield secured to said holder and shaped so as partly to surround a heel-trimming cutter and to enter at its edge the heel-seat groove of a shoe, a guide secured to the bracket, a roll adjustably carried by the holder between the same and said guide, a spring arranged to act on the arm and move the same in the swivel so as to carry the holder toward the guide and cause said roll

to bear thereon, and a spring also acting on said arm to cause the same and the shield holder to move toward an end of the guide.

In testimony whereof I have affixed my signature, in presence of two witnesses.

WILLIAM J. NOON.
